ADJUSTABLE SUPPORT

Edward J. Karp, Cicero, Ill., assignor to G. S. Blakeslee & Co., Cicero, Ill., a corporation of Illinois

Original application April 25, 1941, Serial No. 390,229. Divided and this application July 23, 1942, Serial No. 452,065

2 Claims. (Cl. 248—125)

This invention relates to adjustable supporting means and has to do with an adjustable support for a mixing bowl of a machine intended for use in restaurants, hotels and other establishments in the mixing and treatment of comestibles.

My invention is directed to a support of the character stated slidably mounted on guide means and provided with adjusting means of a character to guard against binding of parts. More specifically, I provide guide rods on which the support is slidably mounted, and an adjusting shaft screwing through a block for adjusting the support, the block having a floating connection to the support effective for preventing binding of parts due to slight inaccuracies in assembly or other causes. Other objects and advantages of my invention will appear from the detail description.

In the drawing:

Figure 1 is a front of a mixing machine, with the lower portion of the head housing broken away and the lower gear housing of the transmission unit omitted for clearness of illustration, showing an adjustable mixing bowl support embodying my invention as applied to that machine; and

Figure 2 is a fragmentary sectional view, on an enlarged scale, taken substantially on line 2—2 of Figure 1, partly broken away.

This application is a division of my copending application for Mixing machine, Serial No. 390,229, filed April 25, 1941.

The mixing machine with which the adjustable support of my instant invention is particularly intended to be used is disclosed in detail in my above identified copending application, and a brief description of that machine will suffice here. It comprises a base 20, conveniently in the form of a casting, a column 21 mounted upon and extending upward from base 20, and a head 22 at the upper end of column 21 extending forward therefrom and providing an overhang 23 overlying the forward portion of base 22. The column 21 and head 22, including the overhang 23, are formed of plate or sheet steel, the elements thereof being secured together in a suitable manner, preferably by welding. An upwardly projecting flange 24 is welded to the upper end of head 22, about the periphery thereof, and receives the lower edge portion of a box-like cover 25, also preferably formed of sheet or plate steel, which thus seats upon the upper end of head 22. Cover 25 is removably secured in position by two screws 26 passing therethrough and threading into the upper arms of two in-

verted L-shaped brackets 27 welded at their lower portions to the inner surface of head 22 at opposite sides thereof.

Overhang 23 of head 22 provides a housing for a transmission unit 33 suitably mounted therein, on a diaphragm plate 29, and comprising an upper gear housing 34, shown in dotted lines, and a lower gear housing 36, indicated by dot and dash lines, supported from housing 34 for rotation about an axis eccentric thereto. The lower gear housing 36 is provided with an eccentric collar 154 through which extends a rotatably mounted driven shaft 38 on which is secured an attaching collar 210 provided with means, comprising a locking pin 212 having an operating handle 214, for securing a beater or other attachment to shaft 38 for rotation therewith and with the lower gear housing 36. The means referred to for securing an attachment to the driven shaft 38 of the transmission unit is disclosed in detail in my copending application for Securing means, Serial No. 430,239, filed February 10, 1942, and need not be further described here. Any suitable means may be provided for that purpose, and it suffices to state that suitable means is provided for securing a beater or other attachment to the driven shaft of the transmission unit, for use in mixing or treating materials in an appropriately disposed mixing bowl.

In order that the bowl may be supported in proper position, I provide vertically adjustable bowl supporting means. The bowl support is of approximately U shape in plan, and comprises two forwardly and outwardly curved arms 38 of angle cross section, each provided, at its rearward end, with an elongated sleeve 39 slidable on a vertical guide rod 99 suitably secured at its lower end to base 20 and extending upward therefrom into overhang 23 and through a plate 91 extending across the overhang and secured to the side walls thereof by welding. The sleeves 39 are connected by a web element 92 having an opening receiving a block 93 provided in its sides with grooves 94 which loosely receive corresponding tongues 92a integral with web 92. Block 93 is centrally bored and threaded for reception of a threaded adjusting shaft 95 screwing through this block and rotatably mounted at its lower end in base 20, shaft 95 being disposed midway between guide rods 90 in parallel spaced relation thereto. The upper end portion of shaft 95 is reduced and passes through and above a bearing bushing 96 mounted through plate 91. Bushing 96 is provided at opposite sides thereof with straight grooves, and guide rods 90 are likewise provided, at their inner sides

and adjacent plate 91, with straight grooves. Locking plates 97 engage into the grooves of bushing 96 and rods 90 and are bolted to plate 91, effectively restraining the guide rods and the bushing, together with shaft 95, against endwise movement. A bevel gear 98 is secured on the upper end of shaft 95 and meshes with a bevel gear 99 secured on a cross shaft 100. Shaft 100 is rotatably mounted through a bushing 101 mounted through one side wall of head 22 and restrained against endwise movement by a locking plate 102, in the same manner as bushing 96. A hand wheel 103, provided with a handle 104, is secured on the outer end of shaft 100 with its hub 105 in contact with the outer end of bushing 101. A stop collar 106 is secured on shaft 100 in contact with the inner end of bushing 101. Shaft 100 is thus restrained against endwise movement. The other or inner end of shaft 100 is rotatably mounted in a bushing 107 mounted through an angle bracket 108 extending between plate 91 and diaphragm plate 29, this bracket 108 being welded to plates 91 and 29, and to the adjacent side wall of head 22. Bushing 107 is retained in position by a locking plate 109 bolted to bracket 108, in the same manner as bushing 101 and bushing 96.

Each of the arms 88 is provided, at its forward end, with a boss 112 in which is secured an upwardly projecting stud 113 for engagement through a corresponding opening in a plate 114 secured to a band 115 extending about a mixing bowl 116. Midway between the plates 114 an arcuate angle strip 117 is secured to band 115, this strip being provided with a rounded rib 118. A locking hook 119 extends upward through a slot 120, in flange 121 at the upper edge of and connecting the arms 88, this hook being pivoted at its lower end on a crank 122 of a rod 123 rockably mounted in arms 88 and confined against endwise movement. Rod 123 extends outward beyond one of the arms 88 and has an operating arm (not shown) secured on its outer end. By turning rod 123 in one direction, hook 119 is moved downward so as to cause the bill of the hook to engage over rib 118. That provides means for locking the bowl 116 to the support in a manner effectively preventing accidental displacement of the bowl. By

turning rod 123 in the other direction, the bowl may be released for removal and replacement as required. It will be seen that by rotating shaft 100 in proper direction, the bowl 116 may be raised or lowered as desired so as to be positioned in proper relation to the attachment carried by the driven shaft of the transmission unit 33. The loose tongue and groove connection between block 93 and the bowl support provides, in effect, a floating connection which accommodates any slight inaccuracy in parts and eliminates possibility of binding. That is of particular advantage in structures formed of sheet or plate metal, in which it is often difficult to obtain accurate alignment of parts.

Changes in construction and arrangement of parts of my invention may be resorted to, without departing from the field and scope thereof, and I intend to include all such variations, as fall within the scope of the appended claims, in this application in which the preferred form only of my invention is disclosed.

I claim:

1. In a mixing machine of the type having a driven attachment receiving shaft and a mixing bowl support slidably mounted on guide rods and adjusted toward and away from the attachment receiving shaft by an adjusting screw shaft confined against endwise movement, a block threaded on the adjusting shaft and having loose connection to the bowl support for adjusting the latter and effective for preventing binding of the bowl support on the guide rods while enabling movement of the block relative to the bowl support.
2. In a mixing machine of the type having a driven attachment receiving shaft and a mixing bowl support slidably mounted on guide rods and adjusted toward and away from the attachment receiving shaft by an adjusting screw shaft confined against endwise movement, a block threaded on the adjusting shaft and having loose tongue and groove connection to the bowl support for adjusting the latter and effective for preventing binding of the bowl support on the guide rods while enabling movement of the block relative to the bowl support.

EDWARD J. KARP.
